BUFFING MACHINE OR THE LIKE

Robert C. Kelley, Muskegon, Mich., assignor to Brunswick Corporation, Chicago, Ill., a corporation of Delaware

Filed Jan. 14, 1963, Ser. No. 73,162

Term of patent 14 years

(Cl. D9—2)

FIG. 2

FIG. 1 is a perspective view of a buffing machine or the like embodying my new design, showing the top, rear and one end thereof; and

FIG. 2 is a perspective view thereof showing the top, front and opposite end thereof with the top handle in raised position.

The dominant features of the design are shown in full lines in the drawings.

I claim:

The ornamental design for a buffing machine or the like, substantially as shown and described.
